UNITED STATES PATENT OFFICE.

AUGUST F. JOBKE, OF PITTSBURGH, PENNSYLVANIA.

MAGNETIC ORE-SEPARATOR.

1,346,544.

Specification of Letters Patent. Patented July 13, 1920.

Application filed April 24, 1918. Serial No. 230,604.

To all whom it may concern:

Be it known that I, AUGUST F. JOBKE, a citizen of the United States, residing at Pittsburgh, in the county of Allegheny and 5 State of Pennsylvania, have invented certain new and useful Improvements in Magnetic Ore-Separators, of which the following is a specification.

My invention relates to improvements in 10 magnetic separators and particularly the active magnetic fields thereof, and its objects are:

1. The increase in working capacity of a separator.
- 15 2. The formation of graded zones in a field formed by two opposing poles of an electromagnetic system.
3. The prevention of eddy currents in a moving separating member owing to its passage through a magnetic field.
- 20 4. The avoidance of the sticking of ore particles to the separating member after its leaving a magnetic field, due to remanent magnetism.

25 In a preferred form of magnetic separator, owing to the efficiency of the arrangement, especially where a high intensity is aimed at, a magnetic member is provided with a wedge shaped edge opposite a magnetic pole, to collect the ore particles and carry them out of the field. The total length of such an edge at a certain speed is the measure of the capacity of the separator. If a ring-shaped member, rotating about its 30 axis, is provided with an edge, its length is limited to a certain dimension, and I therefore provide members arranged with their edges radially and in close proximity to each other, though separated from each 35 other by air-spaces. Since their length can be made considerable with a corresponding extension of the magnet-poles, a relatively large capacity can be obtained.

40 The separating member, being with its separating edge arranged radially to a vertical axis and normal to the direction of its motion, the flow of ore will also be radial and in the direction of the edge. Zones of varying strengths must be provided in a direction at a right angle to and increasing in strength in the direction of the flow of ore and are therefore to be arranged so as to

divide the separating member into several parts belonging to the different zones.

To attain a gradual or zonal variation of 55 field strength at the edge of the separating member, it will be passed through a magnetic field of varying gap-length, since with a larger gap the field is weakened and with a shorter gap it will be strengthened, in 60 other words, the relative reluctance of the field path determines the flux density in the separating member. Arranging the field strength so, that the ore entering the field first meets the weakest part of the same, 65 permits taking out the magnetic particles according to their permeability, and therefore a classification of the components of the ore is accomplished.

70 A metallic body, such as the separating member, in passing through a magnetic field, produces eddy-currents, which depend not only upon the field strength and the speed with which it traverses the field, but also upon the linear dimensions of the same. 75 Since the field strength, speed and length of the working edge of the separating member are the factors which determine the capacity of the separator, they are preferably not reduced, and I have found, that reducing the separating member in one or both dimensions normal to the working edge is effective in increasing the electrical resistance to eddy-currents that will arise, preferably the dimension in the direction of the motion. For the other dimension, which is in the direction of the magnetic flux, a certain length is essential, to enable a satisfactory flux-density or saturation in the separating member to be reached.

75 I have found, that, if a magnetic body, such as an iron strip is magnetized in a field across the flat, i. e., its second smallest dimension, and particles are made to cling to its edges as the magnet-poles, a repellent 80 action takes place upon the reversal of the strip in the field, so that the flux through it is reversed. It is immaterial, whether the reversal is accomplished through the rotating of the strip or of the field itself. The 85 arrangement, which I shall describe, takes advantage of this discovery through the employment of a suitable separating member in conjunction with successive fields of alter-

nately reversed direction, providing a stray flux of the quality described.

In describing my invention, reference may be had to the accompanying drawing, which shows several preferred forms of the same. In all views similar reference characters denote similar parts.

Figure 1 is a sectional view showing a magnetic field formed by an upper and lower magnet-pole with an air gap of varying length and traversed by a separating member rotating about a vertical axis and normally to the direction of the flux. Fig. 2 shows a fractional plane view of a spider carrying a determined number of separating members. Fig. 3 shows a similar view having the separating members slightly curved. Figs. 4 and 5 are two sectional views of the separating members being adapted to vary the form of the field to suit varying requirements. Fig. 6 is a sectional view of the field formed by upper and lower magnet poles and a separating member, the arrangement providing for a distinct separation of the magnetic field into three zones of different strengths, and Fig. 7 is a sectional view similar to Fig. 6, but attaining the formation of distinct zones in a different way.

The pole 1 of an electromagnet with the winding 3 forms with the pole 2 above and separated from it by an air-gap a magnetic field of a substantially vertical direction. A conveyer 4 is provided to pass the ore to be treated through the field. The movable members 5, mounted on a spider 6, which rotates about a vertical axis, traverse the magnetic field normally to the direction, in which the ore on the conveyer 4 travels. The relative velocities of the ore and the members 5 are arranged so that each particle at a certain moment is opposite and below the lower edge of one of the moving members and therefore subject to the magnetic attraction, which results from the magnetic flux being converged from the face of the lower pole to the edge. To make this coincidence more certain the members 5 may be arranged at a certain small angle with the radial direction, as shown in Fig. 2, or they may be curved as shown in Fig. 3. According to the direction in which the rotating members 5 travel, the individual edge of a member may be kept over the same particle for a longer time, than in most magnetic separators, to enable the particle to eventually move itself free from entangling matter, thus securing a more perfect separation.

The field in Fig. 1 is shown as a gradually converging one, and the lower edge of the members 5 is arranged parallel with the conveyer. This will provide for a substantially similar form of field below each part of the edge except as to flux density and

therefore for a gradually increasing attraction toward the inner end of the edge.

In Figs. 6 and 7 I have provided for zones of uniform but distinctly different values in the same field, in order to be enabled to separate materials of different permeabilities from one another, the variation in strength being greater than in other known arrangements. In Fig. 6 I attain this object by providing air-gaps of different lengths on both the upper and lower pole in stepping off the pole shoes 7 and 8. The flux density through the members 5 then varies according to the reluctance of the circuit through the different air-gaps. In Fig. 7 the same object is attained with gaps of equal lengths by providing separate members 9 and 10 which are energized through the straying flux between poles 1 and 2. The principle of a similar arrangement is described in U. S. Patent 1,132,016 and is cited here to show the applicability of my invention.

In Fig. 1 the members 5 are shown as being cast with one end into the non-magnetic spider 6. The other ends must then be free and insulated by an air-space from one another to avoid the occurrence of inductive currents, the direction of which would be radially along the members. Since these currents would produce a certain torque with the field, there would be a serious amount of power required to move the members 5 and therefore they must be avoided.

While a flat strap mounted vertically on edge provides for a perfect separating member 5 in some cases, members with a section according to Figs. 4 or 5 will at times be found advantageous, the former particularly in high intensity fields. Each of these shapes provides a sharp edge at the lower end in order to concentrate the magnetic flux at it, and a flat surface at the top in order to reduce the reluctance by providing a wider flux path through the air. Notches cut in the edge of the members 5, as shown in Figs. 6 and 7 facilitate the formation of uniform zones of different strengths and distinct segregation.

In Figs. 6 and 7 the members 5 are clamped by means of screws or bolts to the spider 6 and insulating material 11 is provided to prevent electrical contact. While in dry separation the use of insulation at this point is not essential, it will be found advantageous as soon as wet separation is attempted, since its thickness is the measure of a resistance in the circuit of galvanic currents which may arise between the iron members 5 and the non-magnetic alloy of spider 6.

Having thus described my invention, what I claim is:

1. In a magnetic separator a separating member between upper and lower magnet-poles, having its largest dimension and a

lower collecting-edge in the direction of the flow of ore and its smallest in the direction of its movement at right angle thereto and to the flow of flux.

5 2. In a magnetic separator a separating member between upper and lower magnet-poles, having its largest dimension and a lower wedge-shaped edge in the direction of the flow of ore and its smallest in the 10 direction of its movement at right angle thereto and to the flow of flux.

3. In a magnetic separator a separating member between upper and lower magnet-poles, having its largest dimension and a 15 lower collecting-edge in the direction of the flow of ore and a radius to a vertical axis, and its smallest in the direction of its movement at right angle thereto and to the flow of flux.

20 4. In a magnetic separator a separating member between upper and lower magnet-poles, and in closer proximity to the upper pole, having its largest dimension and a lower collecting edge in the direction of the 25 flow of ore and a radius to a vertical axis and its smallest in the direction of its movement at right angle thereto and to the flow of flux, and a conveyer between the lower pole and the separating member, parallel 30 to the latter.

5. In a magnetic separator a separating member between upper and lower magnet-poles and in closer proximity to the former having its largest dimension and a lower 35 collecting-edge in the direction of the flow of ore and being with one end connected radially to a spider rotating on a vertical axis, the other end being isolated from another separating member mounted on the 40 same spider, and its smallest dimension in the direction of its movement at right angle to the flow of ore and of the flux, and a conveyer between the lower pole and the separating member, parallel to the latter.

45 6. In a magnetic separator a separating member having its largest dimension and a lower collecting edge in the direction of the flow of ore and traveling in a direction at a right angle thereto and in the direction of 50 its smallest dimension across a magnet-field increasing in strength in the direction of the ore-flow.

7. In a magnetic separator a magnet-field of increasing strength in the direction of the 55 flow of the ore formed by an upper and lower pole with a corresponding decrease of reluctance in the air-gap whose major portion is equally distributed above and below, a separating member, in closer proximity to the upper pole, having its largest dimension and a lower collecting-edge extending therethrough in the direction of the flow of ore and its smallest in the direction of its movement at right angle thereto and to the

flow of flux, and a conveyer between the 65 lower pole and the separating member, parallel to the latter.

8. In a magnetic separator a magnet-field formed by an upper and lower pole, both of which are stepped off abruptly to form zonal 70 gaps of uniform but increasing reluctance opposite to the direction of the flow of ore, a separating member, in closer proximity to the upper pole at the strongest zone, extending with its largest dimension and a 75 lower collecting edge through the field in the direction of the flow of ore and having its smallest dimension in the direction of its movement at right angle thereto and to the flow of flux. 80

9. In a magnetic separator a magnet-field formed by an upper and lower pole, both of which are stepped off abruptly to form zonal gaps of uniform, but increasing reluctance, opposite to the direction of the flow of ore, 85 a separating member, in closer proximity to the upper pole at the strongest zone, extending with its largest dimension and a lower collecting edge through the field in the direction of a radius to the vertical axis of a 90 carrying spider and of the flow of ore and having its smallest dimension in the direction of its movement at right angle thereto and to the flow of flux, and a conveyer between the lower pole and the separating 95 member, parallel with the latter.

10. In a magnetic separator a magnetic field formed by an upper and lower pole with parallel faces stepped off abruptly in a direction opposite to the flow of flux, and a 100 magnetic separating member extending parallel to and across these faces, forming varying but uniform zones at its lower side.

11. In a magnetic separator a separating member, extending with its largest dimension and a lower separating edge in the direction of the flow of ore and at right angle to a magnet-field with zones of uniform but abruptly varying strength in the same direction, with notches in the lower collecting 105 edge at the junction of zones, to segregate the edge into sections with varying but uniform attracting forces. 110

12. In a magnetic separator a separating member, extending with its largest dimension and a lower collecting edge in the direction of the flow of ore and at right angle to the direction of its movement and to the flow of flux, mounted with one end upon a spider, rotatable about a vertical axis, entirely insulated electrically from the spider and another separating member. 115 120

13. In a magnetic separator substantially vertical magnet-fields of alternately opposite directions formed by upper and lower poles located on a circle, having zonal air-gaps of uniform but increased strength, due to decreased reluctance in the circuits 125

through the several zones toward the axis of the said circle and in the direction of the flow of ore, electrically insulated separating members, in closer proximity to the upper poles, extending with their largest dimension and a lower collecting edge, divided by notches into sections corresponding to the said zones, in a substantially radial direc-

tion to a spider supporting one end of the said members and rotating about the said axis, normal to the flow of ore and the magnetic flux, and a conveyer between the lower poles and the separating members, parallel with the latter.

In testimony whereof I affix my signature. 15

AUGUST F. JOBKE.
